(57) **CLAIM**

The ornamental design for a reagent transportation robot, as shown and described.

DESCRIPTION

FIG. 1 is a front, top and right side perspective view of a reagent transportation robot according to the design;

FIG. 2 is a rear, top and left side perspective view thereof;

FIG. 3 is a front view thereof;

FIG. 4 is a right side view thereof;

FIG. 5 is a left side view thereof;

FIG. 6 is a rear view thereof;

FIG. 7 is a top plan view thereof;

FIG. 8 is a bottom plan view thereof;

FIG. 9 is a cross-sectional view taken along line 9-9 of FIG. 3;

FIG. 10 is a cross-sectional view taken along line 10-10 of FIG. 3;

FIG. 11 is a cross-sectional view taken along line 11-11 of FIG. 3;

FIG. 12 is an enlarged view of the portion shown in the dot-dash line box labeled FIG. 12 in FIG. 1; and,

FIG. 13 is an enlarged view of the portion shown in the dot-dash line box labeled FIG. 13 in FIG. 2.

The broken lines illustrate portions of the reagent transportation robot that form no part of the claimed design. The dot-dash line boxes shown in FIGS. 1-2 define the enlarged portions shown in FIGS. 12-13, and form no part of the claimed design.
